(57) **CLAIM**

The ornamental design for a bucket having storage compartments for holding wet floor warning signs, as shown and described.

DESCRIPTION

FIG. 1 is a view in perspective of a first embodiment of the bucket of the invention.

FIG. 2 is a left side view of the bucket of the invention shown in FIG. 1.

FIG. 3 is a right side view of the bucket of the invention shown in FIG. 1.

FIG. 4 is a view in top plan of the bucket of the invention shown in FIG. 1.

FIG. 5 is a back view of the bucket of the invention shown in FIG. 1.

FIG. 6 is a front view of the bucket of the invention shown in FIG. 1.

FIG. 7 is a view in bottom plan of the bucket of the invention shown in FIG. 1.

FIG. 8 is a view in perspective of an alternative embodiment of the bucket of the invention.

FIG. 9 is a left side view of the bucket of the invention shown in FIG. 8.

FIG. 10 is a right side view of the bucket of the invention shown in FIG. 8.

FIG. 11 is a view in top plan of the bucket of the invention shown in FIG. 8.

FIG. 12 is a back view of the bucket of the invention shown in FIG. 8.

FIG. 13 is a front view of the bucket of the invention shown in FIG. 8; and,

FIG. 14 is a view in bottom plan of the bucket of the invention shown in FIG. 8.
